SELF-STORING STORM AND SCREEN COMBINATION

Filed Aug. 5, 1948

UNITED STATES PATENT OFFICE

2,559,005

SELF-STORING STORM AND SCREEN
COMBINATIONRalph L. Brown and Roger E. Zehner,
Anderson, Ind.

Application August 5, 1948, Serial No. 42,674

7 Claims. (Cl. 160—33)

1

This invention relates to door and window units which include one or more screen frames and similar window frames, either of which, or some of each, may be stored away in a closed compartment in a portion of said unit.

The object of this invention is to construct a combination unit door or window having self-contained screen and window frames which may be selectively used as desired.

A further object is to make a unit such as mentioned above, having a closed compartment in a portion thereof for storing the frames which are not being used.

A further object is to make a unit of the above type which is simple in construction and in which it is easy to change the frames as may be desired.

A further object is to include in the above unit three screen frames and three similar window frames, any three of which may be installed in the unit, while the other three are stored out of sight in a compartment extending approximately one quarter of the length of the unit.

Other and more specific objects will appear in the following detailed description of a construction made in accordance with this invention as provided for in the last object mentioned above, having reference to the accompanying drawing, wherein:

Fig. 1 is an elevational view, partly cut away, of a unit constructed in accordance with this invention.

Fig. 2 is an enlarged sectional view taken on the line 2—2 of Fig. 1.

Fig. 3 is a similar view showing the screen frames in use instead of the window frames.

Fig. 4 is a detail sectional view taken on the line 4—4 of Fig. 1.

Fig. 5 is a detail sectional view taken on the line 5—5 of Fig. 1, and

Fig. 6 is a fragmentary elevational view of a portion of the inner face of a side rail showing the transverse groove for the removable reception of a closure for a lower storage space and a support for operatively positioned screens or window frames.

The unit shown in the drawing illustrates the present invention, which however is not limited to the particular number of frames and the particular details shown, but may include any other number of frames and an appropriately sized storage compartment for substantially half of the total number of frames.

The specific structure illustrated comprises a unit made of top and bottom rails 1 and 2 respectively, mortised into the side rails 3 and 4.

2

A pair of grooves 5 and 6 run along the inside of the upper rail 1 and down the inside of the side rails 3 and 4 for approximately three-quarters of their length, the inside edges of the side rails for the remaining quarter of their length being cut out to the depth of grooves 5 and 6 to form a storage space 9 closed by two side panels 7 and 8 set into and screwed to the side and bottom rails by screws 10. A moulding strip 11 may be used to cover the heads of these screws.

Three screen frames 12 and three window frames 13 of similar size are adapted to slide in the grooves 5 and 6, two of the window frames having water shed lips 14 along their lower edges 15 on the outside of the unit, as shown. A spacer bar 15, the width of the space between the grooves 5 and 6, is mortised into the side rails at a level aligned with the lower edge of the third, i. e. the lower, frame 12 or 13 mounted in the grooves. A supporting rail 16, slightly longer than the storage space 9, is slidable into cross grooves 17 in the side rails 3 and 4 adjacent the lower edge of the spacer bar 15, and supports the frames 12 or 13 in place in the groove 5 or 6 as the case may be. It is locked in supporting position by a screw 18 passing through the spacer bar 15. The supporting rail 16 also forms a top closure for the storage space 9.

The storage space 9 is provided with a pair of spring spacers 19 and 20 of sufficient strength to hold the three frames in storage against rattling. They may be rubber coated or plain metal leaf springs, and may be shifted from one side of the space to the other, as may be convenient when storing different frames from opposite side grooves in the unit.

An examination of the drawing will reveal the advantages of the novel features of this construction. The screen frames and the storm window frames are kept handy in the same unit, and will not get lost or become dirty or damaged, as might be the case if they are separately put away. They are always matched and obviate the necessity of matching the right frame for the right unit, when several units are used.

The change from one type of frame to the other is very easily performed. One of the panels may be removed to facilitate the change over. However, the change may be made without removal of either panel. It is only necessary to remove the screw 18 to unlock the supporting rail 16 so it may be slid from under the vacant groove 5 or 6, while still supporting the frames in the other groove, then the unit may be turned up-side-down and the frames in the storage

space 9 can be guided into the vacant groove one at a time. Then the supporting rail 16 is moved over the third frame, past its normal position in the unit until it uncovers the other groove, whereupon the unit is righted again, and the frames in the other groove may then be guided into the storage space 9 one at a time, allowing each frame to move its upper edge toward the other panel before starting the next frame to slide along side of it. When the last of the three frames is slid into the storage space against the pressure of the springs 19 and 20 acting through the other frames, the supporting rail is slid back into its normal place covering the storage space, and the screw 18 is fixed to lock it in place.

As already mentioned, the number of frames used may be altered and other obvious modifications in the details of structure may be made without departing from the spirit and scope of this invention, as defined in the appended claims.

What is claimed is:

1. A storm and screen unit comprising end and side rails, means on said rails for supporting one or more superposed screen frames between a portion of said side rails, and storage means for the same number of similarly sized storm frames between the remaining portion of said side rails, the vertical edges of the frames in the storage means at the inner faces of the side rails and being facewise to each other, there being a passageway between the superposed and the stored portions of the frames, said supporting means normally closing said passageway, whereby to provide a self-contained replaceable storm and screen frame combination.

2. A storm and screen unit as defined in claim 1, wherein said supporting means includes a groove around the inside of the upper and side rails, and the storage means includes a storage space co-extensive with the lateral limits of said groove, whereby the frames are slidable from said groove into said space and vice versa.

3. A storm and screen unit as defined in claim 1, wherein said supporting means includes a pair of spaced grooves running around the inside of the upper and side rails, and the storage means includes a space co-extensive with the lateral limits of said frame-receiving grooves, whereby the frames are slidable between said grooves and said storage space for selective use and storage of the different frames.

4. A storm and screen unit as defined in claim 3, wherein said storage space is closed by the lower and side rails, a panel on each front and back side of the storage space, there being grooves across the inside of said side rails over the top of said panels, and a supporting rail slidably mounted in said last mentioned grooves, for holding the frames in either of said pair of frame-receiving grooves.

5. A storm and screen unit as defined in claim 4, wherein said supporting means further includes a spacer bar between said side rails having substantially the same width as the space between said pairs of frame-receiving grooves, and being fixed contiguous to the supporting rail and between the pairs of frame-receiving grooves, and means on said spacer bar for locking said supporting rail in normal position.

10 6. A storm and screen unit as defined in claim 1, wherein said supporting means includes a groove around the inside of the upper and side rails, a horizontal supporting rail slidable to project from the side rails at either side between said portions and leave an opening at either side in line with opposed frame-receiving grooves of the side rails, and the storage means includes a storage space co-extensive with the lateral limits of said groove with which the grooves of the side rails communicate, whereby the frames are slidable from said groove into said space and vice versa.

15 7. A storm and screen unit comprising a rectangular frame including parallel top and bottom rails, and side rails, respectively, said top and side rails having a pair of spaced aligned frame-receiving grooves at the inside thereof, the grooves at the sides terminating in spaced relation to the bottom rail, a horizontal spacer bar fixed between said side rails having substantially the same width as the space between said pairs of frame-receiving grooves, a horizontal supporting rail slidably mounted between the side rails at the bottom of the spacer bar and movable into and out of the side rails at the opposite faces of the frame at the lower ends of the frame-receiving grooves to form a storage space in the lower portion of the frame and passageways for interchangeable movement of screen and window frames to and from the grooves to the storage space, and means to anchor the supporting rail to the spacer bar to close the top of the storage space.
